UNITED STATES PATENT OFFICE

FRED D. HOLDSWORTH, OF CLAREMONT, NEW HAMPSHIRE, ASSIGNOR TO SULLIVAN MACHINERY COMPANY, A CORPORATION OF MASSACHUSETTS

COMPRESSOR CONTROLLING MECHANISM

Application filed November 24, 1928, Serial No. 321,743. Renewed June 4, 1931.

This invention relates to a mechanism for controlling a prime mover as the load carried by the same varies. In another and more limited aspect, my invention relates to controlling mechanisms for internal combustion engines employed in the driving of air compressors and other pumping devices.

In modern internal combustion engines, which as a general rule are provided with devices for igniting the explosive mixture, the timing of the ignition is commonly automatically controlled in accordance with the speed of the load carried by the engine. The engine is therefore principally controlled by regulation of the feed of the combustible mixture to the engine; and the speed of the engine and the machine driven thereby is maintained, as the load increases, by feeding a greater volume of mixture. Accordingly, one object of my invention is to provide improved means for controlling the supply of explosive mixture to an internal combustion engine as the demand made upon the same varies. A further and more specific object of my invention is to provide improved means for controlling the supply of explosive mixture to an internal combustion engine which is employed as the prime mover for an air compressor or other pumping device, increasing or decreasing the supply in accordance with the demands made by the compressor. A still further object of my invention is to provide improved means for varying the supply of fuel to the engine which drives an air compressor in accordance with the loading and unloading of the compressor, providing for ensuring the acceleration of the engine before loading is effected. Other objects and advantages of the invention will be apparent from the following description and more particularly pointed out in the claims.

In the accompanying drawings, in which for purposes of illustration, one embodiment of my invention is shown,—

Fig. 1 is a side elevation of a compressor mechanism in which the illustrative embodiment of the invention has been incorporated.

Fig. 2 is a sectional view through the intake and discharge valves of one cylinder of the compressor, the figure showing an un-

loading device which cooperates with the inlet valve.

Fig. 3 is a view in side elevation of the fuel supply control, a portion of the controlling mechanism being shown in section.

Fig. 4 is a section on line 4—4 of Fig. 3.

In Fig. 1 of the drawings a portable compressor outfit is illustrated, the same comprising a motor 7 and a compressor 8 both mounted on the frame 9 of a wheeled truck. The outfit is provided with a fuel tank 10, and with a receiver 11 to which the air or other fluid being compressed is delivered by way of the connection 12. The compressor is provided with suitable inlet and discharge valve mechanism. In Fig. 2 is shown a portion of one of the cylinders of the compressor, with which cooperates a valve casing 13 within which is disposed a discharge valve 14 and an inlet valve 15. A cylinder 16 in the form of an inwardly projecting member 16^a is formed integral with a cap 17 secured to the end of the valve casing 13. The cap 17 is perforated at 18 to permit the air to enter the valve casing. A piston 19 is reciprocable within the cylinder 16; and the cylinder 16 and the piston 19 cooperate to act as a servo-motor to which fluid under pressure is supplied by way of a pipe connection 20. The piston 19 carries a stud or bolt 21 which supports a pronged member 22. The prongs of the latter are adapted to engage the inlet valve as the piston 19 nears the inner end of its travel within the cylinder 16. When the inlet valve 15 is so engaged it is lifted, and held off its seat so as to unload the compressor.

The engine 7 is provided with an intake supply connection 23 within which is disposed a butterfly valve 24 (see Fig. 3). A fluid pressure responsive device 25 controls the same, being connected thereto by a linkage 26. The device 25 comprises a casing having two aligned bores 27 and 28. A pipe connection 29 delivers fluid at receiver pressure to the bore 27. Within the latter is reciprocable a piston 30. Within the bore 28 is disposed a second piston having a sleeve-like portion 31 and a head portion 32, the latter portion being, if desired, secured to

the end of the piston 30. At 33 are pivotally supported rollers, mounted on the fork 34 of a lever 35, and moved oppositely by pistons 30 and 32. The lever 35 pivots about a pin 36 which is carried by the casing of the device 25; and the other end of the lever 35 is pivotally connected to the linkage 26.

The portion of the casing of the device 25 which is adjacent the bore 28 is provided with two passages 37 and 38 which meet adjacent the surface of the device in a threaded opening, into which is threaded a pipe connection 39. The inner end of the passage 37 communicates with the bore 28. The sleeve member 31 acts as a valve to control the passage 37, since a groove 40 is formed in the periphery of the sleeve member 31 and an orifice 41 opens from the interior of the sleeve member 31 into the groove 40. As the sleeve member 31 reciprocates, the groove 40 is carried into and out of communication with the passage 37.

An end member 42 is secured in any suitable manner to the portion of the device 25 in which bore 28 is formed. The end member 42 is provided with a chamber 43 which is aligned with the hollow interior of the sleeve member 31. A threaded screw 44 projects into this chamber, being provided with a lock nut 45. A spring 57 is disposed within the sleeve member 31. One end of this spring abuts the end of the bore in the sleeve member 31 and the other end is provided with an abutment member 58 against which bears the end of the screw 44. A second chamber 46 is provided in the end member 42, into which leads a passage 47 which opens at its other end into the chamber 43. A continuation 38' of the passage 38 opens into the chamber 46. A threaded plug 48 is screwed into the open end of the chamber 46. A valve 49 has a stem 50 which is guided in the plug 48, a spring 51 being adapted to press the valve 49 against a seat 52 which is formed in the member 42 at the junction of the passage 47 and the chamber 46. A pipe connection 53 is threaded to a passage 53' which opens into the chamber 43. As shown in Fig. 1, the pipe connection 53 leads to a pilot valve 54 which is connected by piping 55 to the receiver 11. The connection 29 branches off of this same pipe line 55. The pipe connection 39 leads by way of piping 56 to the connections 20 which lead into the motors for the unloading devices. The pilot valve 54 is of the type which supplies actuating fluid to the mechanism controlled thereby when the receiver pressure exceeds a predetermined maximum and vents the mechanism to atmosphere when the receiver pressure falls a predetermined amount below such maximum.

The operation of the control device when the motor is being started is as follows. It will be assumed that the receiver 11 is empty,

This may have taken place if the compressor has been standing a long time. On the other hand, the receiver may be empty due to intentional opening of a vent valve. With the receiver empty, the piston 30 may be forced inwardly; and therefore the spring 57 has thrown the butterfly valve towards closed position. The engine is now started; and as the pressure in the receiver builds up, the pressure in the bore 27 increases, gradually throwing the lever 35, and therefore gradually opening the butterfly valve 24, the spring 57 resisting such movement of the piston 30. When the pressure in the receiver 11 has reached the normal working pressure for which the compressor is designed, the butterfly valve 24 will be in open position. The screw 44 may be adjusted to suitably position the spring for this purpose.

Should the demand for pressure fluid fall off, the pressure in the receiver 11 may reach such a point as to actuate the pilot valve 54. When this action takes place the pilot valve delivers fluid through the connection 53 into the chamber 43, this fluid being under the same pressure as the fluid in the bore 27. It will be noted that the bore 28 however, is substantially larger than the bore 27; and the sleeve-like member 31 is therefore immediately moved outwardly so as to shift the lever 35 and throttle down the engine. The pressure fluid in chamber 43 also acts against the valve 52, unseating the same so that the fluid may be delivered through passage 38 and connections 39, 56, 20 to the 100 motors of the unloading devices. The compressor is therefore unloaded.

When the pressure in the receiver 11 falls to the predetermined minimum pressure at which the pilot valve 54 is set to effect re-loading, a vent in the pilot valve 54 will be opened, and the pressure in the chamber 43 will immediately fall. The closing of the check valve 49 has, however, trapped the pressure fluid within the pipe connections 39, 56, and 20 and within the cylinder 16. The fluid pressure behind sleeve member 31, however, is vented, since the bore 28 is connected to atmosphere by way of pilot valve 54. Since full receiver pressure is acting within the bore 27, the piston 30 will move outwardly, pushing sleeve member 31 within the bore 28, thereby opening the butterfly valve 24 and once more speeding up the engine. Just before the sleeve member 31 reaches the position illustrated in Fig. 3, the pressure fluid which has meanwhile been holding the compressor unloaded is vented through passage 37, groove 40, the opening 41, the chamber 43, the connection 53, and the vent in the pilot valve 54. It will therefore be noted that the compressor is not loaded again until the butterfly valve 24 controlling the supply of fuel to the motor has been nearly completely

opened thereby bringing the engine and compressor up to speed.

It will be obvious from the above description that, in accordance with my invention, 5 the control mechanism supplies fuel to the engine in accordance with the demands made upon the engine. As the pressure in the receiver 11 increases, more and more fuel is supplied to the engine, so that it is able to 10 carry the load of compressing the fluid to receiver tank pressure. It should further be noted that as soon as the compressor is unloaded the supply of fuel to the motor is immediately cut down so as to prevent racing 15 of the motor. When the pilot valve, due to a decrease in receiver pressure, functions to vent air from the chamber 43, the check valve 49 prevents immediate reloading of the compressor. This provides an opportunity for 20 the motor to come up to speed before the load is placed on the motor, it being obviously advantageous to have the motor at its working or ordinary running speed before the load is placed thereon. As, however, the engine 25 throttle nearly reaches its full open position, the groove 40 begins to register with passage 37 and reloading of the compressor takes place.

While I have in this application specifically 30 described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a controlling mechanism for a compressor system comprising a compressor and a motor for driving the same, in combination, unloading means for the compressor including actuating means adapted to be subjected to pressure to effect unloading of the compressor, movable means for controlling the relief of such pressure to cause loading of the compressor, movable means for controlling the speed of said driving motor, and an expandible chamber motor for moving simultaneously said first and second mentioned movable control means to effect the loading of the compressor and an increase in the speed of said driving motor, the chamber of said expandible chamber motor being normally subjected to the pressure of the discharge of the compressor.

2. In a controlling mechanism for a compressor system comprising a compressor and a motor for driving the same, in combination, unloading means for the compressor including actuating means adapted to be supplied with medium under pressure to effect unloading of the compressor, means for controlling the exhaust of such medium for causing loading of the compressor including a movable

element, a second movable element for controlling the speed of said driving motor, and an expandible chamber motor for moving simultaneously said first and second mentioned movable elements to effect the loading of the compressor and an increase in the speed of said driving motor, the chamber of said expandible chamber motor being normally subjected to the pressure of the discharge of the compressor.

3. In a controlling mechanism for a compressor system comprising a compressor and a motor for driving the same, in combination, an unloading device for the compressor, means for supplying actuating medium to said unloading device, means for controlling the supply of such medium to said unloading device and the venting of the same from said unloading means including a check valve adapted to maintain the compressor unloaded, movable means for controlling the speed of said driving motor, and a servo motor for simultaneously causing venting of pressure medium from said unloading device to effect loading independently of said check valve and moving said motor speed control means.

4. In a controlling mechanism for a compressor system comprising a compressor and a motor for driving the same, in combination, movable means for controlling said driving motor, a servo motor for actuating the same, said servo motor comprising a yieldable member having a surface subjected to fluid at the compressor discharge pressure, unloading means for the compressor, and means comprising a pilot valve and an element actuated by said servo motor for controlling said unloading means whereby unloading and loading of the compressor are controlled in response to variations in the compressor discharge pressure and in accordance with the position of said motor control.

5. In a controlling mechanism for a compressor system comprising a compressor and an internal combustion engine for driving the same, in combination, a throttle for said engine, a servo motor for actuating said throttle, said servo motor comprising a yieldable member having a surface subjected to fluid at the compressor discharge pressure acting in a direction for opening said throttle, unloading means for the compressor, and controlling means for said unloading means comprising a pilot valve responsive to compressor discharge pressure for delivering pressure fluid for actuating said unloading means and for venting such fluid, said unloading controlling means providing a passage, flow of fluid through which in one direction is controlled by said servo motor.

6. In a controlling mechanism for a compressor system comprising a compressor and an internal combustion engine for driving the same, in combination, a throttle for said

engine, a servo-motor for actuating said throttle, said servo motor comprising a yieldable member having a surface normally subjected to fluid at the compressor discharge pressure, unloading means for the compressor, means for supplying actuating medium to said unloading means comprising a pilot valve responsive to compressor discharge pressure, and means interposed between said unloading means and said pilot valve for controlling flow of fluid in one direction, said last mentioned controlling means being actuated by said servo motor to prevent loading of the compressor until the engine comes up to speed.

7. In a controlling mechanism for a compressor system comprising a compressor and a motor for driving the same, in combination, movable means for controlling said driving motor, a servo motor for actuating the same, said servo motor comprising a yieldable member having a surface normally subjected to fluid at the compressor discharge pressure, unloading mechanism for the compressor, means comprising controlling mechanism responsive to compressor discharge pressure for delivering actuating medium to said unloading means, and means controlled by said servo motor for holding said compressor unloaded until said driving motor comes up to speed.

8. In a controlling mechanism for a compressor system comprising a compressor and a motor for driving the same, in combination, means for controlling the speed of said driving motor, a servo motor for actuating the same, said servo motor comprising a yieldable member having a surface normally subjected to fluid at the compressor discharge pressure, unloading means for the compressor having a connection to a source of actuating medium, controlling means interposed in said connection to control said unloading means, said controlling means including a member actuated by said servo motor and a yieldable member independent of said servo motor and having a surface normally subjected to compressor discharge pressure during unloading.

9. In a controlling mechanism for a compressor system comprising a compressor and a motor for driving the same, in combination, means for controlling the speed of said driving motor, a servo motor for actuating the same, said servo motor comprising a yieldable member having a surface normally subjected to fluid at the compressor discharge pressure, fluid pressure actuated unloading means for the compressor, a pilot valve responsive to compressor discharge pressure for controlling the supply of pressure fluid to said unloading means, and supplemental means including a valve for controlling return flow of fluid from said unloading means, said supplemental means being actuated by

said servo motor and operating to hold said compressor unloaded until the compressor driving motor comes up to speed.

10. In a controlling mechanism for a compressor system comprising a compressor and an internal combustion engine for driving the same, in combination, a throttle for controlling the speed of the engine, a servo motor for actuating the same, said servo motor comprising a yieldable member having a surface normally subjected to fluid at the compressor discharge pressure, fluid pressure actuated unloading means for the compressor having a connection to a source of pressure fluid, a pilot valve interposed in said connection and responsive to compressor discharge pressure for controlling said unloading means, and supplemental means including a valve interposed in said connection for controlling return flow of fluid from said unloading means, said supplemental means being actuated by said servo motor and operating to hold said compressor unloaded until the engine comes up to speed.

11. In a compressor controlling mechanism for a compressor system comprising a compressor and a motor for driving the same, in combination, an unloading device for the compressor for unloading the same when subjected to pressure, means for controlling the supply of actuating medium to said motor, fluid pressure responsive means for actuating said motor controlling device to a position increasing the supply of actuating medium to said motor when subjected to pressure, fluid pressure responsive means for actuating said motor controlling device to a position cutting down the supply of actuating medium to said motor when subjected to pressure, a pilot valve for controlling simultaneous supply of pressure fluid to said unloading device and said last mentioned fluid pressure responsive means, said pilot valve also controlling exhaust of pressure fluid from said device and means, and means for preventing exhaust of fluid from said unloading device until the motor controlling device is moved to substantially open position.

12. In a controlling mechanism for a compressor system comprising a compressor and motor for driving the same, in combination, an unloading device for unloading the compressor, a throttle valve for controlling the supply of actuating medium to said motor, a device for automatically controlling said throttle valve, said automatic device having a surface normally subjected to fluid at the compressor discharge pressure acting in a direction for opening said throttle valve and an opposed surface, said automatic device functioning to cut down the supply of actuating medium to said motor when said opposed surface is subjected to pressure, a common means responsive to compressor discharge pressure for controlling supply and

- exhaust of pressure fluid to and from said opposed surface and said unloading device, and means for preventing loading of said compressor until said throttle valve has moved to substantially open position.
- 5 13. In a controlling mechanism for a compressor system comprising a compressor and a motor for driving the same, in combination, an unloading device for unloading the compressor when subjected to pressure, a 10 throttle valve for controlling supply of actuating medium to said motor, means continuously responsive to compressor discharge pressure for controlling said throttle valve, superior control means for said throttle valve comprising a fluid actuated device for taking the control of said throttle valve away from said first mentioned controlling means and moving said throttle valve to closed position 15 when subjected to pressure, means for simultaneously supplying pressure fluid to said unloading device and the fluid actuated device of said superior controlling means when the compressor discharge pressure reaches a predetermined maximum and for venting said 20 superior motor controlling device when the compressor discharge pressure reaches a predetermined maximum, and means for venting said unloading device only after a predetermined movement of said fluid actuated device of said superior controlling means.
14. In a controlling mechanism for a compressor system comprising a compressor and a motor for driving the same, the combination specified in claim 13 wherein said vent means for said unloading device comprises valve means operated to open position upon movement of said fluid actuated device of said superior controlling means to a position corresponding to substantial opening of said 40 throttle valve.
15. In a controlling mechanism for a compressor system comprising a compressor and an internal combustion engine for driving the same, in combination, a throttle for said engine, a servo motor for actuating said throttle, said servo motor comprising a yieldable member having a surface normally subjected to fluid at the compressor discharge 45 pressure, unloading means for the compressor, and controlling means for said unloading means comprising means affording a conduit for pressure fluid moving to or from said unloading means, a check valve in said 50 conduit permitting flow of fluid to said unloading means and preventing return flow therefrom, means affording a passage bypassing said check valve, a valve controlled by said servo motor controlling flow through 55 said by-pass passage, and a pilot valve responsive to compressor discharge pressure for delivering pressure fluid to said conduit for actuating said unloading means and for venting such fluid by way of said by-pass 60 passage.
16. In combination, a compressor, a driving motor therefor, a member movable to control the speed of said compressor, a plunger subjected continuously to compressor discharge pressure for moving said member in a direction to increase the compressor speed, an aligned oppositely acting plunger yieldably biased in the opposite direction, and means for subjecting said last mentioned plunger to compressor discharge pressure when the latter exceeds a predetermined desired maximum and for venting pressure supplied thereto upon a predetermined drop in pressure below said desired maximum.
17. In a pumping system, a pump, a driving motor therefor, controlling means for the driving motor movable to vary the speed thereof, a plunger constantly subjected to compressor discharge pressure for moving said controlling means in a direction to increase the compressor speed, an oppositely acting combined plunger and valve member, and compressor unloading means including a compressor discharge pressure responsive pilot valve, pressure operated unloading devices, and a one way conduit means between said pilot valve and said devices, said second plunger controlling venting of the unloading devices and being controlled by the pilot valve to slow down the compressor when unloading is effected.
18. In a motor driven compressor system including an internal combustion engine and a compressor driven thereby, controlling means for the compressor speed including a plunger constantly exposed to compressor discharge pressure, an oppositely acting plunger constantly biased in a direction opposite to the first mentioned plunger and having associated therewith means for supplying pressure thereto when compressor discharge pressure exceeds a predetermined desired maximum, a throttle for said internal combustion engine, and operating connections for said throttle disposed between said plungers and actuated in opposite directions thereby.
19. In a controlling mechanism for a compressor system comprising a motor, a compressor and an unloader therefor adapted for fluid pressure control, the combination including motor controlling means, a servo motor for moving said motor controlling means in one direction, and a superior servo motor for moving the controlling means in the opposite direction, said second servo motor having a portion thereof constituting a valve for the control of the fluid pressure for the unloader.
20. In a controlling mechanism for a compressor system comprising a motor, a compressor and an unloader therefor adapted for fluid pressure control, the combination including motor controlling means, a servo motor constantly responsive to compressor dis-

charge pressure acting in a direction to move the motor controlling means in a speed increasing direction, and a second servo motor for actuating the motor controlling means, said second servo motor having a piston comprising a valve for the control of the fluid pressure for said unloader.

21. In a compressor system, a compressor, fluid operated unloading means therefor, a driving motor for said compressor, a device for controlling the motor speed, a member constantly subjected to compressor discharge pressure and arranged to move said device, superior controlling means for said device, 10 adapted to be operated by fluid pressure, and a single receiver pressure responsive pilot valve for controlling the supply of operating fluid for both of said means, said pilot valve controlling the exhaust from one of said means and the latter means being constructed and arranged to control the exhaust from 15 the other of said means.
20. In testimony whereof I affix my signature.

25 FRED D. HOLDSWORTH.
